UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed September 26, 1922. Serial No. 590,643.

To all whom it may concern:

Be it known that I, ALONZO E. RHOADES, a citizen of the United States, and a resident of Hopedale, county of Worcester, 5 State of Massachusetts (whose post-office address is Hopedale, Massachusetts), have invented an Improvement in Feeler Mechanism for Looms, of which the following description, in connection with the accompanying drawing, is a specification, like characters on the drawing representing like parts.

This invention relates to a feeler mechanism for effecting automatically a change in 15 the operation of the loom when the filling in the working shuttle has become substantially exhausted but while sufficient filling still remains on the filling carrier to insure the weaving of perfect cloth. The change 20 in the operation of the loom thus affected may, for example, be the stopping of the loom or it may be and frequently is the replenishment of a fresh supply of filling such as takes place in the well known automatic filling replenishing loom. Various 25 forms of feeler mechanism have been designed for accomplishing this object but this invention relates more particularly to that type of feeler mechanism employing 30 what is commonly termed a "needle feeler." This type of feeler mechanism comprises a feeler member having a small point which is adapted to sink into the mass of filling upon each detecting beat of the lay without 35 effecting the operative movement of the feeler member until the filling has become exhausted to the required degree whereupon the point of the feeler member comes into contact with the hard surface of the filling 40 carrier and upon the ensuing beat up of the lay is given an operative movement.

One object of the present invention is to 45 provide a feeler mechanism of the needle type in which this needle or penetrating feeler member is normally held in a retracted position so as not to engage and penetrate or sink into the filling thus preventing any injury or damage being done thereby to the filling and in which this penetrating 50 member is only projected so as to engage the filling when the filling has been exhausted to a predetermined extent or is approaching the degree of exhaustion desired for effecting the change in the operation of the loom.

Another object of the invention is to pro-

vide a feeler mechanism of this type in which a governing or controlling feeler member in the form of a "side slip" feeler is given an indicating movement upon the exhaustion of the filling to a predetermined extent and thereby or therethrough acts to bring the filling penetrating member into position to engage and feel the filling.

A further object of the invention is to provide in this type of feeler mechanism a means acting normally to retract the filling penetrating member, an actuator for effecting the change in the operation of the loom and an intermediary means in the form of a wedge which, upon the indicating movement of the "side slip" feeler member, is pulled or drawn between the actuator and the filling penetrating member to project the filling penetrating member and effect a connection between the filling penetrating member and the actuator thereby to cause the actuator to move into actuating position when the filling penetrating member engages the filling carrier upon the beat up of the lay.

The nature and objects of the invention will appear more fully from the accompanying description and drawings and will be particularly pointed out in the claims.

In the drawings:

Fig. 1 is a top plan view of a feeler mechanism embodying a preferred form of the invention;

Fig. 2 is a side elevation of the construction shown in Fig. 1, together with certain portions of the loom mechanism;

Fig. 3 is a detail partially in top plan and partially in transverse cross section showing the co-operation of the feeler mechanism and filling carrier to effect the movement of the actuator into actuating position.

The feeler mechanism of this invention may be embodied in looms of various types and may be employed for securing any desired change in the operation of the loom but, as in the case of the feeler mechanisms embodied in my prior inventions above referred to, it is particularly designed for use on an automatic filling replenishing loom of the well known "Northrop" type where it is employed to initiate the filling replenishing operation upon the substantial exhaustion of the filling in the running shuttle. It is, therefore, unnecessary to illustrate or describe the general construction

and operation of the loom. As herein shown the mechanism is designed to move forwardly the end of a controller 1 and the movement of this controller through 5 suitable transmitting mechanism acts to effect the desired change in the loom.

The feeler mechanism is shown as mounted upon a bracket 2 which may be attached to the breast beam or other fixed portion of 10 the loom opposite the shuttle box at the detecting side of the loom. In Figure 3 this shuttle box 3 is shown mounted on the lay 4 and containing the boxed shuttle 5 with its filling carrier or bobbin 6. Openings 7 15 in the front wall of the shuttle box and 8 in the shuttle permit the entrance of the feeler mechanism therethrough so as to engage with the filling carrier in the usual manner.

The feeler stand comprises a base 9 secured to the bracket 2 by bolts 10 and a top portion 11 cast in suitable form and secured to the base by the screws 12. This feeler stand is provided with a suitable longitudinal groove in which is mounted for longitudinal sliding movement toward and from the lay a feeler slide 13. This slide is in the form of a flat plate reduced at its front portion 14 to form a shoulder 15. A coiled spring 16 surrounds the reduced portion 14 and abuts against the shoulder 15 and a shoulder 17 on the feeler stand and thus acts normally to project the feeler slide 13 rearwardly or toward the lay.

The rearward end of the feeler slide 13 is provided with a cover plate 18 held in place by screws 19. The rearward surface 20 of the slide 13 and cover plate 18 may at times during the operation of the loom impinge upon the filling of the filling carrier, but this 40 impinging face does not constitute one of the effective elements of the mechanism as in the usual type of "needle" or filling penetrating member feeler mechanism. Its main purpose is to serve as a guard for the filling penetrating member and prevent the comparatively sharp pointed filling penetrating member from contacting with the filling during the normal operation of the loom and until the filling is very near to the degree of substantial exhaustion at which the feeler mechanism is to act to effect the desired change in the operation of the loom.

The filling penetrating member is in the form of a flat plate 21 mounted to slide longitudinally in a groove between the feeler slide 13 and top plate 18 at the rear end of the slide. This plate 21 carries at its rearward end the point or needle 22. The center portion of the plate 21 is cut out to form a pocket for a spring 23 abutting at its forward end against the plate and at its rearward end against a stop 24 on the feeler slide. This spring therefore acts normally to hold the filling penetrating member retracted and

with its point in front of the face 20 as shown 65 in Figures 1 and 2.

The actuator is in the form of a bell crank lever having a long forwardly extending arm 25 and a shorter depending arm 26. This bell crank lever is fulcrumed at 27 on a bracket 28 projecting upwardly from the feeler slide 13. The rearward end of the feeler stand terminates in an upstanding bracket 29 in which is mounted a plunger 30 normally depressed by a spring 31 which acts to hold the arm 25 of the actuator downwardly and cause it under normal conditions to be guided during the reciprocating movement of the feeler slide beneath the end of the controller arm 1. When the actuator is moved by the action of the feeler mechanism into actuating or operative position the arm 25 is raised against the tension of the spring 31 and its forked end 32 comes into line with the end 80 of the controller arm 1 and as the feeler slide 13 moves forwardly carries along the controller arm and thus gives the desired movement for initiating a change in the operation of the loom. A stop lug 33 provided 85 with an adjustable stop screw 34 is mounted on the feeler slide and acts, if necessary, to insure the return of the controller arm to normal position.

The controlling or governing feeler member in the preferred form of this invention is in the form of a "side slip" feeler and has connected therewith an intermediary means in the form of a wedge which is drawn or pulled into position between the filling penetrating member and the actuator arm 26 thereby to effect the desired initiating movement of the feeler mechanism upon the exhaustion of the filling to the required degree.

This "side slip" feeler is shown in the form of a bell crank lever 35 fulcrumed at 36 on the feeler slide. The arm 37 of this lever extends alongside the feeler slide to the rear end thereof and at its effective end is toothed or roughened at 38. The other arm 39 of the lever seats against a spring 40 held in the bracket 28. This spring therefore normally acts to hold the side slip feeler with its arm 37 substantially parallel with the feeler slide, and with the roughened end 38 well to the rear of the face 20 of the feeler slide. The intermediary or wedge member 41 is pivotally connected at 42 to the feeler member 35 and extends between the depending arm 26 of the actuator and the forward end of the filling penetrating member slide 21. This member 41 is widened out or cam or wedge shaped at its free end and is so constructed that, when the feeler mechanism is in the normal position as shown in Figures 1 and 2 and the filling penetrating member slide 21 is in its retracted position and the actuator is in its normal position, this member 41 will just about fill the space between.

If, however, the side slip feeler member 35 is swung away from the feeler slide 13 the wedge member 41 is drawn or pulled between the slide 21 and the actuator arm 26.

8 The operation of the mechanism will now be apparent. Under normal conditions the parts stand as shown in Figures 1 and 2. As the lay beats up on a detecting beat the feeler members pass through the openings 7 and 8 in the shuttle box and shuttle and the roughened surface 38 of the side slip feeler contacts with the filling and as the beat up continues the entire feeler slide moves forwardly, the actuator arm 25 passing beneath the controller arm 1, and all the parts carried by the feeler slide remain unmoved with respect thereto. The filling on the filling carrier is gripped by the roughened surface 38 and so no movement of the side slip 15 feeler takes place with respect to the feeler slide. The spring 23 holds the filling penetrating member retracted and any contact which may take place between the filling and the surface 20 is unnecessary and has no 20 effect.

When, however, the filling on the filling carrier has become reduced or exhausted to such an extent that the surface of the filling carrier opposite the roughened surface 38 of the side slip feeler member is bare or contains but a loose layer or so of filling the pressure of the filling carrier against the roughened surface 38 as the lay beats up will permit the surface 38 to slip on the 35 filling carrier and the entire feeler member 35 will rock about its pivot 36. As this rocking movement takes place the wedge member 41 is drawn or pulled in between the filling penetrating member and the actuator arm 26 thus projecting the filling penetrating member against the action of its spring 23 which is much weaker than the spring 31 until upon the same or successive beat ups the point 22 sinks through the remaining filling on the filling carrier and engages the hard surface of the filling carrier. When this takes place and the beat up continues the filling carrier, pushing against the filling penetrating member and through 40 the rigid connection established by the wedge 41 between it and the actuator, raises the actuator against the tension of the spring 31 to bring its forked end 32 into line with the end of the controller arm 1 and thereupon as the beat up continues further the entire feeler slide moves forwardly carrying with it the controller arm and effecting the desired change in the operation of the loom.

After the desired change has been initiated and the lay beats back the feeler slide moves rearwardly under the influence of the spring 16 in the usual manner. The spring 31 returns the actuator to normal position and the spring 40 returns the side slip feeler member to its normal position and thereby

the wedge is pushed to the left to disconnect the actuator and the filling penetrating member. The filling penetrating member is again retracted under the influence of its spring 23.

70 There is thus provided a very simple, efficient and accurate detecting mechanism.

Having thus described my invention, what I claim as new, and desire to secure by Letters Patent, is:

75 1. A feeler mechanism for looms comprising a filling penetrating member, means acting normally to retract the filling penetrating member, an actuator acting when moved into actuating position to effect a change in the operation of the loom, a side slip feeler member, and means operated by the side slip of the side slip feeler member to project the filling penetrating member and to effect a connection between it and the actuator whereby upon the contact of the filling carrier with the filling penetrating member upon the beat up the actuator will be moved to actuating position.

80 2. A feeler mechanism for looms comprising a feeler slide, means for normally projecting the feeler slide rearwardly, an actuator movably mounted upon the feeler slide, a filling penetrating member movably mounted on the feeler slide, means acting normally to retract the filling penetrating member, a side slip feeler member movably mounted on the feeler slide, a wedge shaped intermediary member operated by the side slip feeler member and moved upon the side slip of said member and acting, first, to project the filling penetrating member and, second, to effect a connection between the filling penetrating member and the actuator whereby, upon the contact of the filling carrier with the filling penetrating member upon the beat up, the actuator will be moved to actuating position.

85 3. A feeler mechanism for looms comprising a feeler slide, means acting normally to project the feeler slide rearwardly, a filling penetrating member slidably mounted in the feeler slide, means acting normally to retract the filling penetrating member, an actuator movably mounted on the feeler slide, a side slip lever feeler member fulcrumed on the feeler slide, a wedge shaped intermediary member pivoted to the side slip member and extending between the filling penetrating member and the actuator, the side slip movement of the side slip feeler member acting to draw the wedge portion of the intermediary member between the filling penetrating member and the actuator and thereby, first, to project the filling penetrating member and, second, to effect a rigid connection between it and the actuator.

90 In testimony whereof, I have signed my name to this specification.

ALONZO E. RHOADES.
